UNITED STATES PATENT OFFICE

105,838

DESIGN FOR A WARMING OVEN OR THE LIKE

Hans Bruning and Otto Schuller, Hanau, Germany, assignors to the firm W. C. Heraeus, G. m. b. H., Hanau, Germany

Application May 27, 1937, Serial No. 69,588

Term of patent 14 years

To all whom it may concern:

Be it known that we, Hans Bruning and Otto Schuller, both citizens of Germany, residing in Hanau, Germany, have invented a new, original, and ornamental Design for Warming Ovens or the like, of which the following is a specification, reference being had to the accompanying drawing, forming part thereof.

Fig. 1 is a perspective view of a warming oven or the like showing our design; and

Fig. 2 is a side elevational view thereof on a slightly smaller scale.

We claim:

The ornamental design for a warming oven or the like, as shown.

HANS BRUNING.
OTTO SCHULLER.
